RECOVERY OF CYCLODIENES WITH VAPOR PHASE CRACKING

Joseph F. Nelson and Fred W. Banes, Westfield, and Addison W. Hubbard, Cranford, N. J., assignors to Esso Research and Engineering Company, a corporation of Delaware

Application November 16, 1953, Serial No. 392,322

4 Claims. (Cl. 260—666)

This invention relates to a process for recovering high-purity cyclopentadiene and methyl cyclopentadiene from crude concentrates of their dimers, codimers, trimers, and cotrimers, subjected to a vapor phase cracking. The vapor phase cracking is made more efficient by including a continuous undercutting step for removing certain high-boiling ends between a tubular preheater of the feed and the cracking tube. Preheating of the crude dimers, codimers and higher polymers in a continuous stream partly maintained in liquid phase followed by continuous removal of the heavier liquid ends of the preheat feed brings about a significant reduction in coking of the cracking tube.

Vapor phase cracking of the cyclodiene dimers and higher polymers can give higher conversions to the monomers as compared to liquid phase cracking, but a serious problem associated with vapor phase cracking is the coking of the cracking tube. It is known that in the past some proposed processes have dealt with vapor phase cracking of a very narrow boiling range cyclopentadiene dimer fraction substantially free of other cyclopentadiene polymers. It has been indicated that for such vapor phase cracking large amounts of gaseous diluents or other measures should be employed to prevent undesired formation of coke and/or high polymer resins. Such measures described in the past have not been found suitable for a process of recovering both cyclopentadiene monomer and methylcyclopentadiene monomer from a crude mixed dimer and polymer stream. For one thing, the use of a large amount of gaseous diluent can be upsetting to the recovery of the separate monomers. Also difficulties arise in making a suitable separation of heavy ends between a feed preheater and a cracking tube if gaseous diluents are used improperly.

The technique of the present invention is designed to minimize coking of the cracking tube while obtaining improved recovery of both high purity cyclopentadiene and methyl cyclopentadiene. It has been demonstrated to be efficient without the use of any gaseous diluent.

The invention will be described by reference to the flow diagram in the drawing. Here the crude feed of cyclodiene dimer and polymers is supplied by line 1 to the preheater 2 surrounded by suitable heating medium as in furnace 3. A high boiling recycle fraction is admixed through line 4 with the feed entering the preheating tube 2.

The preheating tube 2 operates with an outlet temperature of about 250° to 300° F. and with pressures of about 1 to 30 p. s. i. a. maintained therein. Using a liquid feed rate of 15 to 50 volumes per unit vaporizer volume per hour the feed may be almost completely

2

vaporized on leaving the outlet of the preheating tube 2. Since there is always some liquid flow in this preheating or vaporizing tube and since temperatures are below 300° C., no coking occurs while an appreciable amount of cracking of dimer takes place therein.

The preheated liquid and vapor mixture is discharged from the outlet of the preheater tube 2 to line 5 into the flash drum 6. The drum 6 acts as a bottoms knock-out to continuously remove heavy ends boiling mainly above about 275° C. to 280° C. while vaporized and partially cracked products are separated, e. g., withdrawn overhead by line 7. The bottoms are continuously withdrawn through line 8 from drum 6. Baffles, 9, provided in the upper part of drum 6 help to knock out entrained heavy ends which are to be prevented from entering the cracking tube or coils, 10, with the vapors sent therethrough through line 7.

The cracking tube 10 is heated by surrounding heating gases or heating means as in furnace 11.

20 In the cracking tube 10, the cracking of the dimers, codimers, trimers and cotrimers of the C₅—C₆ cyclo-dienes is completed at temperatures of 350° to 450° C. in contact times of 0.5 to 3.5 seconds. To obtain short contact time a vapor velocity in the range of 200 to 300 25 feet per second is used. With the refractory type high boiling polymers absent, coking difficulties are substantially reduced in the cracking tube.

If any gaseous diluent is to be added, e. g., steam or inert hydrocarbon gas, it would be introduced into 30 the flash drum 6 through inlet 12. The introduction of the diluent means a decrease in capacity with a unit designed to operate without the use of a diluent.

The cracking tube effluent is passed from an outlet of the cracking tube 10 through a heat exchange cooler 35 13 by line 14 into an intermediate part of a splitter tower 15. The splitter tower 15 is a fractionating means for removing cyclopentadiene and methyl cyclopentadiene monomers continuously as an overhead vapor stream and continuously removing dimers and higher polymers as a bottoms. The overhead vapor stream is taken off from tower 15 through line 16. The bottoms are withdrawn from tower 15 through line 17. A portion of the bottoms may be recycled through line 18 and 40 reboiler 19 to a bottom part of the tower 15. Another portion of the bottoms may be purged from the system through line 20. Any desired portion of the bottoms may be passed through line 21 into the recycle line 22 for return to the preheater feed line 1.

50 The splitter tower 15, equipped with about 10 to 15 plates for fractionation is operated at an overhead temperature of about 50—60° C. using reflux ratio of from 1:1 to 5:1. The overhead monomer vapors may be cooled in condenser 23 in being passed to the receiver 24. Reflux is returned to the upper part of tower 15 55 through line 25. Distillate of the monomer is passed from receiver 24 through line 26 into the next fractionating column 27.

If steam distillate has been used in the cracking tube 60 water condensate would have to be withdrawn through line 28. Any gaseous diluent would be removed from receiver 24 by vent line 29. A suitable bottoms temperature in the splitter tower 15 is of the order of 160° to 170° C. An intermediate fraction of C₇—C₉ hydrocarbons, such as would include C₇ cyclodienes, is advantageously purged as a side stream 30 below the feed inlet of tower 15. The overhead distillate from the

splitter tower 15 supplied to the next tower 27 should be principally C_5 and C_6 cyclodienes. Some dimerization and further polymerization takes place in the splitter tower 15 to yield the bottoms which may be recycled to the preheater coil 2.

Column 27 which is used for separating the C_5 and C_6 cyclodiene monomers may be fed at a midpoint with the mixture of the monomers and may be provided with about 30 plates. In column 27 the overhead product is taken off at a vapor temperature of about 40° to 43° C. at a reflux ratio of 2:1 to 5:1. Generally it is preferable for this overhead product to be a high purity cyclopentadiene monomer.

The methyl cyclopentadiene product is advantageously taken off as a side stream from a lower part of the column 27, below the feed inlet, e. g., at about the 5th plate from the bottom and at a temperature of about 73° – 80° C. In column 27, additional dimerization and polymerization occurs to yield a bottoms product.

The bottoms is withdrawn from column 27 through line 36. A portion of the bottoms may be recycled through reboiler 37 and line 38. Any portion of the bottoms from column 27 which will not be re-cracked may be purged through purge line 39. The portion of the bottoms from column 27 to be re-cracked may be recycled by way of line 22 and line 4 to the inlet of the preheater coil 2. A mixed purged stream may be removed from the system through line 41. Some purging is desirable to prevent the buildup of high boiling polymers and other fill in the recycle streams. Ordinarily, it is desirable to hold the recycle rate in the range of $\frac{1}{2}$ to 5 halves of the fresh feed.

The general kind of crude feed for which the present process is adapted is one which will contain about 35 to 45% cyclopentadiene (CPD) in the form of dimer and codimers, 30 to 35% methyl cyclopentadiene (MCPD) in the form of dimer and codimers and contain in the remaining 35 to 20%, C_7 cyclodienes and acyclic dienes as dimers and codimers, and some aromatics and higher polymers. It will have an initial boiling point of about 135° C. and contain 94–98 volume percent boiling up to about 280° C. and from 2 to 6 volume percent boiling higher than about 280° C. A more detailed analysis of a representative fresh feed is shown in the following Table I.

TABLE I
Analysis of fresh feed

[Vacuum Dist.]

Cut No.	Boiling Range, °C. at 1 Atmos.	Wt. Percent on Feed	Wt. Percent of Total in Fraction	
			CPD	MCPD
1.....	134–157	12.51	4.5	3.9
2.....	157–170	4.27	5.3	1.7
3.....	170–171	11.12	20.9	3.5
4.....	171–175	11.22	21.7	5.7
5.....	175–184	10.56	15.1	11.5
6.....	184–187	11.24	12.0	16.7
7.....	187–193	10.50	10.5	17.2
8.....	193–199	10.33	4.3	20.9
9.....	199–209	9.49	3.4	13.2
10.....	209–280	3.26	2.1	5.0
11.....	Residue	5.50	0.2	0.7

The total feed in this case contained 36.1 wt. percent CPD and 36.8 wt. percent MCPD. These data, as well as those from which the figures in Table I were derived, were obtained by cracking the feed or fractions thereof at 400° F. The monomer products thus formed were then subjected to mass spectrometer analyses.

Another sample of feed was cracked at 400° F. and analyzed for total CPD and MCPD in the manner described above. A sample of this same feed was then analyzed directly in the mass spectrometer to determine the quantities of dimers and codimers. These data are given in Table II.

TABLE II
Analysis of fresh feed

	Mass No.	Wt. percent on Total Feed
Cyclopentadiene (as monomer).....	66	37.5
CPD Combined in Feed as CPD Dimer.....	132	21.0
CPD Combined in Feed as CPD-MCPD Codimers.....	146	14.4
Methylcyclopentadiene (as Monomer).....	80	33.9
MCPD Combined in Feed as MCPD Dimer.....	160	12.7
MCPD Combined in Feed as MCPD-CPD Codimer.....	146	17.4
Wt. percent of CPD as:		
CPD Dimer.....		56.0
CPD-MCPD Codimers.....		38.5
Wt. percent of MCPD as:		
MCPD Dimer.....		37.5
MCPD-CPD Codimers.....		51.3

The data in Table I and Table II illustrate that the cyclopentadiene is present as dimers and codimers which form fractions boiling as high as 195° C. The cyclopentadiene dimer is difficult to isolate and would require a precise fractionation to obtain a narrow boiling fraction boiling in the restricted range of 160° to 180° C. and removal of such a narrow fraction would result in the loss of cyclopentadiene which is present in the form of codimers and trimers. Thus, in order to realize high recoveries of cyclopentadiene it is necessary to use a cracking feed boiling as high as 195° C. or higher. If methylcyclopentadiene is also to be recovered the feed endpoint is 210° C. or preferably 275° – 280° C.

EXAMPLE 1

When using the feed described in Table I and operating the preheating or vaporizing tube with an outlet temperature of 225° C. then undercutting the preheater effluent in a knockout or flash drum, a purge stream of heavy material representing 2 volume percent of the feed was continuously removed as bottoms. When this heavy purge material was subjected to cracking at 425° C. there was recovered only 12% of cyclopentadiene and methylcyclopentadiene monomers based on the amount of purge stream and at the same time there was considerable coke formation in the cracking tube. In comparison thereto the material which is vaporized at up to 280° C. and thus removed from the knockout drum is easily cracked completely at 400° C. leaving no coke residue.

EXAMPLE 2

A fraction of the feed described in Table II, containing 37.5 wt. percent CPD and 33.9 wt. percent MCPD as dimers and codimers, was cut to have a boiling range of about 270° to 276° C. so as to contain cyclopentadiene trimer. This material was easily cracked at 400° C. at 1.5 seconds contact time with relatively little coke formation. The recovered cyclopentadiene monomers represented 97% of the theoretical yield. In contrast, cracking materials including tetramers of the cyclodienes boiling above 280° C. gave very low yields of the C_5 – C_6 cyclodiene monomers and caused excessive coke formation.

This indicates the refractory nature of the components boiling above the range of the C_5 to C_6 cyclodiene trimers, i. e., boiling above 280° C.

EXAMPLE 3

A concentrate of cyclodiene dimers, codimers and higher boiling components, yielding 42.2% cyclopentadiene, 34.4% methyl cyclopentadiene with 5% of C_7 cyclopentadienes, C_5 acyclic dienes, and 14% of other hydrocarbons including aromatic, olefins and high boiling polymers, was used in a series of vapor phase cracking experiments. The overall feed boiled in the range of 135° to above 280° C., 95 volume percent distilling off at about 280° C. The feed was cracked at 400° C. in 1.5 seconds contact time at a vapor velocity of 2.5' per second. The total run length was 15–20 hours.

After each run the cracking tube was washed thoroughly with a light hydrocarbon to remove any soluble residue and the remaining insoluble residue deposited on the tubes was burned out at 1100° F. by passing air through the tube. The combustion gases were caught in a conventional Drierite-Ascarite type train to determine the amount of water the carbon dioxide evolved. These gas evolutions were used to estimate the quantities of coke deposit in the cracking tube. Data illustrating the advantages of continuously undercutting the cracking feed to prevent material boiling above 280° C. from entering the cracking tube is shown in the following table:

Table III
Relation of coke deposits to feeds

	Wt. Percent undercutting on Total Feed	Wt. Percent Coke Deposition based on Total Feed
Dimer Concentrate—No recycle	0	0.045
Dimer Concentrate with 117% Recycle	0	0.083
Dimer Concentrate with 117% Recycle	1.09	0.045
Dimer Concentrate with 122% Recycle	2.0	0.013
Dimer Concentrate with 122% Recycle	5.0	ca. 0.007

It is evident from data such as shown in Table II that continuous removal of high boiling refractory bottoms from fresh and recycle feed is necessary. It is also necessary to remove a certain amount of the fresh feed or mixed feeds by undercutting to prevent high boiling materials boiling about 280° C. from entering the cracking tube. Thus it can be seen that it is desirable to have any recycle which is to be admixed with the fresh feed pass through the preheater or vaporizer to be subjected to the similar undercutting.

Examination of the cracking tube before burn out showed that coke tended to be deposited at the entrance of the high temperature cracking tube when heavy ends boiling above 280° C. were permitted to enter the cracking tube and these deposited residues were the chief source of coke.

Having described the invention it is claimed as follows:

1. A process of recovering C₅ and C₆ cyclodiene monomers which comprises preheating in a continuous stream a crude condensate containing cyclodiene dimers, codimers, trimers and cotrimers, boiling in the range of about 135° to 280° C. and a minor amount of higher boiling components boiling above about 280° C., said higher boiling components containing cyclodiene tetramers which when subjected to vapor phase cracking form coke, preheating said condensate to vaporize the dimer, codimer and trimer components, boiling up to about 280° C., maintaining said higher boiling components including the cyclo-

diene tetramers in liquid phase, separating the vaporized components which boil in the range of 135° to 280° C. from the liquid phase and subjecting to vapor phase cracking said vaporized components free of components higher boiling than 280° C. including cyclodiene tetramers at temperatures in the range of about 350° to 450° C.

5 2. In a process as described in claim 1, subjecting said crude mixture to preheating in a continuous stream of restricted cross section, passing the resulting vapors and residual liquid into a vapor separation zone in which liquid components higher boiling than 280° C. are separated from the remaining vapors of said stream, and subjecting said remaining vapors in continuous stream of restricted cross section to the vapor phase cracking.

10 3. In the recovery of C₅ and C₆ cyclodienes as monomers from a crude mixture of their dimers, codimers, trimers, cotrimers and higher polymers, preheating said mixture to vaporize components boiling up to 280° C., separating components thereof boiling above 280° C. including said higher polymers as liquids, vapor phase cracking the separated vapor components kept free of said components boiling above 280° C. in a continuous stream, cooling the vapor phase cracked vapor components and introducing them into a first fractionation zone, separating 20 an overhead distillate of cyclopentadiene and methyl cyclopentadiene from said first fractionation zone, removing a side stream of C₇ to C₉ components in a lower part of said first fractionation zone below its feed point, and withdrawing a liquid dimer containing fraction from a bottom part of first fractionation zone, passing the overhead distillate from said first fractionation zone into an intermediate part of a second fractionation zone, distilling overhead from said fractionation zone cyclopentadiene monomer, withdrawing a side stream of methyl cyclopentadiene monomer between the bottom and the feed inlet of said second fractionation zone and withdrawing dimer containing liquid bottoms from a bottom part of said second fractionation zone, and recycling dimer-containing bottoms fractions from said fractionation zone to the preheating zone.

30 4. In the process of claim 3, supplying an inert lower boiling diluent to the vapors passed through said vapor phase cracking zone, and separating said diluent from the overhead distillate of the first fractionation zone before the hydrocarbon distillate containing cyclopentadiene and methyl cyclopentadiene is supplied to said second fractionation zone.
